G. M. BEAN.
OIL BURNING LOCOMOTIVE FURNACE.
APPLICATION FILED AUG. 3, 1914.

1,138,067.

Patented May 4, 1915.

UNITED STATES PATENT OFFICE.

GUY M. BEAN, OF LOS ANGELES, CALIFORNIA, ASSIGNOR, BY MESNE ASSIGNMENTS, TO AMERICAN ARCH COMPANY, OF NEW YORK, N. Y., A CORPORATION OF DELAWARE.

OIL-BURNING LOCOMOTIVE-FURNACE.

1,138,067.

Specification of Letters Patent.

Patented May 4, 1915.

Application filed August 3, 1914. Serial No. 854,785.

To all whom it may concern:

Be it known that I, GUY M. BEAN, a citizen of the United States, and a resident of Los Angeles, county of Los Angeles, and 5 State of California, have invented certain new and useful Improvements in Oil-Burning Locomotive-Furnaces, of which the following is a specification.

My invention relates to locomotives and 10 oil burning apparatus therefor and the object of my invention is to increase the efficiency and the reliability of such apparatus.

In the ordinary arrangement and construction of the oil burning apparatus of locomotives, the oil burner proper is supplied 15 with steam from a remote part of the boiler through a pipe or pipes wholly or in part exposed to the weather and the quality of the steam emerging from the nozzle of the 20 burner constantly varies with the conditions encountered. Variation from this cause is accentuated by the varying quality of the steam furnished by the boiler at different times. Oil which is atomized by a jet of 25 dry steam burns readily in the firebox of a locomotive, whereas the presence of any considerable proportion of free moisture, as in relatively cool wet steam, markedly diminishes the efficiency of the burning jet 30 from the burner.

The specific object of my invention is to overcome the variation in efficiency here indicated and to make the operation of oil burners sure and reliable under all conditions. To this end I superheat the steam on 35 its way to the burner and in the immediate proximity thereof, as by means of a superheating element, situated in the firebox and in close connection with the burner thereof.

40 My invention will be more readily understood by reference to the accompanying drawings forming a part of this specification, illustrating the invention in preferred form, and in which:—

45 Figure 1 is a vertical longitudinal section of the lower part of the rear end of a locomotive boiler and its firebox; Fig. 2 is a partial sectional view on the line 2—2 of Fig. 1; and Fig. 3 is an enlarged longitudinal and vertical section taken from Fig. 1 50 disclosing the burner proper and the superheating arrangement.

The drawings disclose a typical locomotive firebox A and its oil burning bottom or

pan B. As is usual the dropped portion B¹ 55 of the pan is shorter than the firebox to leave space for the burner and its piping. The space between the end of the dropped portion B¹ and the flue sheet A¹ of the firebox is closed by a substantially horizontal 60 floor or shelf B². The dropped portion of the pan contains the main entrance and burner opening B³. Auxiliary air inlets B⁴ are sometimes used in the side walls of the pan. As shown, the pan and its marginal 65 shelf portions are lined or floored with refractory bricks C. On the shelf portion B² I provide two layers of bricks, C¹ being the lower layer and C² the upper layer, for a purpose about to be described. 70

D is the oil burner proper supported in the opening B³.

E is a valved oil supply pipe connected with said burner proper D.

F is a valved pipe which leads from the 75 dome (not shown) of the boiler, to supply steam to the burner D. In practice, the valves e and f of the pipes E and F are preferably arranged for control from the cab of the locomotive, the showing of said valves 80 e and f herein being diagrammatic.

F¹ is the steam connection of the burner D. There are two steam courses between the pipe F and connection F¹. One of these courses includes a superheater and the other 85 constitutes an emergency by-pass. The superheater proper is preferably a coil or series of U-bends G, embedded in the refractory brick flooring or lining of the firebox bottom or pan B. The most stable part of 90 the lining is that upon the shelf B², and I therefore select this part to contain the superheating coil G, and for convenience in embedding the coil, make this portion of the lining in two layers, as before mentioned. 95 Ordinarily, to better contain the coil G, I form one or both layers with a groove or recess C³, in which the coil is fully incased and protected from direct contact with the flame in the firebox. A pipe G², containing 100 a shut-off valve G³, connects the steam pipe F with the end G⁴ of the superheating coil G. And the pipe G⁵, containing a shut-off valve G⁶, connects the end G⁷ of the superheating coil G with the steam connection 105 F¹ of the burner D. The by-pass, before mentioned, comprises a pipe F² containing a shut-off valve F³ and joining the steam pipe

F with the steam connection F¹ of the burner D. Steam, of a quantity which varies as before mentioned, is supplied from the boiler through the pipe F. During the normal action of the apparatus the valves f in the steam pipe F and e in the oil pipe E are regulably open; and the valves G³ and G⁶ in the superheater connections are also open, whereas the by-pass valve F³ is closed. 5 Steam, therefore, flows freely from the pipe F and passes through the superheating coil or element G on the shelf in the firebox to the burner D. The flame, which is ignited and burns from the burner B, normally 10 keeps the firebox A at a high temperature and the refractory lining C (including C¹, C²) is therefore normally hot. It follows that although the steam entering the superheating coil may be very wet and contain 15 considerable free moisture, it will be superheated in passing through the coil, and will therefore emerge from the burner D and take on its burden of oil in a state best adapted to the atomization of the latter and 20 combustion in the firebox. In event of a break or leak in the superheating coil, the valves G³ and G⁶ are closed, and the valve F³ is opened to temporarily supply steam to the burner, through the direct emergency 25 course or by-pass F².

As various modifications of my invention will readily suggest themselves to one skilled in the art, I do not limit my invention to the structure herein shown, except as stated in 30 the appended claims.

Having thus described my invention, I claim as new and desire to secure by Letters Patent:

1. A locomotive boiler and its firebox, in combination with a pan which closes the bottom of the firebox, and having a substantially horizontal shelf portion, said pan and shelf being floored with refractory material, a burner beneath said shelf and positioned to project a stream of oil and steam into said pan, an oil supply pipe connected with said burner, and a superheating coil embedded in the refractory material on said shelf and having its ends connected with the boiler and burner respectively, for the purposes described. 40

2. A locomotive boiler and its firebox, in combination with a pan which closes the bottom of the firebox and having a substantially horizontal shelf portion, carrying two layers of refractory bricks, a burner beneath said shelf and positioned to project a stream of oil and steam into said pan, an oil supply pipe connected with said burner, and a superheating coil positioned between said 55 layers of bricks and having its ends connected with the boiler and burner respectively, for the purposes described. 60

In testimony whereof, I have hereunto set my hand this 31st day of March, 1914, in the presence of two subscribing witnesses.

GUY M. BEAN.
